UNITED STATES PATENT OFFICE

CARL OTTO, OF HELLERUP, DENMARK, AND CHARLES W. ANDREWS, OF DULUTH,
MINNESOTAAPPARATUS AND PROCESS FOR PRODUCING COKE AND WATER GAS IN VERTICAL
CHAMBER OVENS

Application filed May 8, 1925. Serial No. 28,832.

Our invention relates to an apparatus and process for producing water gas in vertical chamber coke ovens and more particularly to a means for regulating the coking time and for supplying steam to the top of the charge, enriching it if desired with oil or heavy hydrocarbons and drawing off the water gas at the bottom of the oven thru a separate pipe.

10 It will be understood that in order to more readily discharge the coke from vertical chamber and retort ovens, at their bottoms, these have been built tapering, with walls narrowing toward the top and widening downwardly. The consequence is, that the coal in the upper part will coke more rapidly than the coal in the lower part. In order to achieve a uniform coking in the entire height of the oven, it was necessary 15 to decrease the amount of heating when coking toward the top, according to the thickness of the coal charge.

20 In producing water gas in such chamber or retort ovens, the steam was supplied from the bottom; the operator waiting to feed the gas until the whole coke charge had expanded.

According to our invention, one increases 25 in a given time the amount of coal that is charged and coked and the amount of production of gas in vertical chamber coke ovens by heating the upper part of the oven just as much as the lower part is heated.

This heating of the coking chamber is 30 accomplished by any suitable means. Turning to the drawing, in which the figure illustrates a vertical section of a vertical chambered coke oven, a recuperator system is illustrated in which strong rich gas is supplied through pipes M to heating flues N, to which preheated air for combustion is supplied, the burning gases passing alongside of the outside of the coking chamber and returning for discharge into flues O.

45 By this means the upper part of the charge becomes coked and expands some hours earlier than the lower part. Distillation gases then pass upwardly and out through pipe A, valve C and main D. In order to prevent 50 a superheating of the upper part of

the charge, steam from pipe B, is supplied to the standpipe A, after coking the upper part of the charge, the valve C, to the collector gas main D, having been closed, thus cutting off the discharge of the distillation 55 gases. The steam which enters the coke chamber E, produces water gas from contact with the expanded coke in the upper part of the chamber. This water gas then passes to the lower part of the chamber 60 which has not yet been completely coked and because of the sensible amount of heat which it carries, helps in the coking operation. The water gas which has been produced is discharged at the lower end of the coke 65 chamber or retort, with the distillation gas, which is still being produced, into the pipe F, which is provided with a shut-off valve G.

In order to make easy the discharge of 70 the gas through the entire horizontal width of the coking chamber, it is preferred to fill the lower part of the chamber with pieces of coke H, before filling the chamber with 75 coal.

In order to produce gas of high calorific 80 value, one can supply oil or tar in the upper part of the chamber through pipe B, if desired with or without the steam, which will produce a carbureting of the water gas 85 which is formed in the oven, when steam is used.

Having thus described the invention, its 90 operation will be clear. It will be understood that changes may be made in carrying the invention into effect without departing 95 from the principle thereof.

What we claim is:

1. The process of producing coke and 90 water gas in vertical chamber coke ovens, which consists in coking the upper portion of the coal in the chamber of the oven, feeding steam to the top of the chamber after the ending of the coking of the coal in the upper part of the chamber and before ending 95 of the coking in the lower part of the chamber, and in drawing off the water gas so produced, at the bottom of the chamber, with the distillation gas which is still being produced.

2. The process of producing coke and water gas in vertical chamber coke ovens with downwardly widening coking chambers, which consists in coking the upper portion of the coal in the chamber of the oven, feeding steam to the top of the chamber after the ending of the coking of the coal in the upper part of the chamber and before ending of the coking in the lower part of the chamber, supplying heavy hydrocarbons into the chamber at the top in order to carburet the water gas thus formed, and in drawing off the water gas so produced, at the bottom of the chamber.
3. The process of producing coke and water gas in vertical chamber coke ovens with downwardly widening coking chambers, which consists in coking the upper portion of the coal in the chamber of the oven, feeding steam to the top of the chamber after the ending of the coking of the coal in the upper part of the chamber and before ending of the coking in the lower part of the chamber, supplying oil into the chamber at the top in order to carburet the water gas thus formed, and in drawing off the water gas so produced at the bottom of the chamber.
4. An apparatus for producing coke and water gas in vertical chamber coke ovens comprising in combination, a vertically elongated oven chamber having downwardly widening walls, and adapted to discharge coke through the bottom, means for heating the outside of the oven chamber so as to coke the upper portion of the coal, means for discharging distillation gases from the top of the chamber, means for feeding steam to the upper part of the chamber, and means including a pipe for drawing off the water gas so produced, from the bottom of the chamber.
5. An apparatus for producing coke and water gas in vertical chamber coke ovens comprising in combination, a vertically elongated oven chamber having downwardly widening walls and adapted to discharge thru the bottom; means for heating the outside of the oven chamber so as to coke the upper portion of the coal, means for discharging distillation gases from the top of the chamber, means for cutting off said discharge of the distillation gases, means for feeding steam to the upper part of the chamber, and means for drawing off the water gas and distillation gases from the bottom of the chamber.

In witness whereof, we have signed our names to this specification.

60   CARL OTTO.
                         CHARLES W. ANDREWS.
